UNITED STATES PATENT OFFICE.

WILLIAM Y. GAMBEE, OF NEW YORK, N. Y.

DUMPING-SCOW.

SPECIFICATION forming part of Letters Patent No. 721,883, dated March 3, 1903.

Application filed September 24, 1902. Serial No. 124,623. (No model.)

To all whom it may concern:

Be it known that I, WILLIAM Y. GAMBEE, a citizen of the United States, and a resident of Bronx borough, city, county, and State of New York, have invented certain new and useful Improvements in Dumping-Scows, of which the following is a specification.

This invention relates more particularly to the class of dumping-scows shown in the patent to Daniel Delehanty, No. 542,408, of July 9, 1895; and it consists in providing the dumping-scows, in which several pockets are arranged in a row, with improved means for opening and closing the doors of such pockets. Heretofore the raising and lowering devices have generally been located within the pockets and have therefore been in the way of the discharge of the load. They have also required the use of braces to support the walls of the pocket, owing to the fact that the strain of raising the heavy doors, which form the bottom of the pocket, tends to draw the walls of the pocket together.

The object of my invention is to do away with these braces and all other obstructions to the speedy discharge of the pocket. To that end I form the end walls of the pocket hollow and place the raising and lowering devices inside such walls. I also arrange these raising and lowering devices so that the strain caused by the weight of the doors is sustained by the end walls, which thereby prevent any tendency in the side walls to collapse.

In the accompanying drawings I have shown one set of raising and lowering devices as arranged at one end of one of the pockets, it being understood that a similar device is provided at each end of each of the pockets which the scow has.

Figure 1 is a section looking from line 1 1 of Fig. 2, the inner wall being removed. Fig. 2 is a section on line 2 2 of Fig. 1.

Same letters indicate similar parts in the different figures.

A is a pocket of usual construction forming part of the dumping-scow, (not shown,) having the side walls *a a* and end walls *b b*. The end walls are hollow, as shown in Fig. 2, and in the space between the inner plate *c* and outer plate *d*, of which said wall is composed, are arranged the raising and lowering devices. The pocket is provided with the usual

doors *e e*, which overlap, as shown at *f*, and are hinged to the bottom of the walls *a a*, as shown at *g g*. The doors are shown closed in full lines in Fig. 1 and open in dotted lines. On the inner face of the wall-plates *c d* I have provided an inclined track, consisting of the rails *h i*, upon which run the cars *j j*. The rails *i i* are secured to the wall-plate *d* by suitable rivets (not shown) or otherwise, and extend from near the bottom of the wall to a point at any convenient height on the face of the plate to provide an easy run for the cars *j j* from their descent. The rails *h h* are similarly located on the other wall-plate *c*, and a portion of the car *j* projects downward to the space between the rails *h i* and is attached to one of the doors *e e* by a cable or chain *l*. The car *j* is provided with a flange *k*, located beneath the rails to prevent its jumping the track, and with the wheels *m m*, running upon the rail. The position of the car when the doors are closed is shown in full lines in Fig. 1 and is shown in dotted lines when the doors are open.

At convenient places upon the wall *b* are arranged the grooved rollers *n n*, over which the car-chains *o o* pass. The lower end of each chain is attached to a car *j*, and the free end is turned around a drum *p* of usual construction. The means for winding or releasing these chains to raise or lower the doors are of usual construction, consisting of the drum *p* and worm-gear *q*, mounted upon the deck *r* and turned by the worm *s*. These devices are mounted upon the deck of the scow in the usual way, there being one set of such devices at the end of each pocket and all driven from the engine or other source of power. (Not shown.)

It will be readily understood that the weight of the doors is at all times supported by the end walls *b* and that the strain caused by that weight is primarily at all times a direct downward strain. The excess only of the strain which is not supported by the wall *b* through the tracks *h i* is exerted upon the drum *p* and that within the line of the wall *b*, so that the said wall acts in this regard as a permanent brace for the side walls.

I claim—

1. A dumping-scow provided with suitable pockets the bottom doors of which are sup-

ported by raising and lowering devices mounted upon the end walls of said pockets and guided by rollers moving on inclined tracks whereby the strain in raising and lowering said doors falls within the vertical and horizontal lines of said walls substantially as set forth.

2. A dumping-scow provided with suitable pockets with hollow end walls, tracks located within said hollow walls inclined to each

other and extending from the center line of said walls to the opposite lower corners, cars adapted to move along said track and means substantially as described connected with said cars whereby the doors of said pocket are raised or lowered as desired.

WILLIAM Y. GAMBEE.
